CAN CLOSING MACHINE

Archibald N. York, Geneva, N. Y., assignor to
 American Can Company, New York, N. Y., a
 corporation of New York

Application September 11, 1936, Serial No. 100,394

14 Claims. (Cl. 113—82)

The present invention relates to container or can closing machines of the type which have valves for moving the cans into and out of a vacuumized can closing chamber, the invention having particular reference to a hoisting mechanism, embodied in the machine and utilized for raising the valves out of their seats so that they may be cleaned and lubricated and for returning them again to position within their seats.

Proper care in cleaning and lubricating the valve seats and valves of vacuum can closing machines is essential in maintaining a tight fit between valve and seat to insure against loss of vacuum in the closing chamber. These valves are usually ponderous and heavy and hard to manage although proper care requires that they be removed frequently. Canning factories where the machines are used to seal filled cans are usually not equipped with machinery for handling these valves and hence considerable difficulty is sometimes experienced in properly cleaning and lubricating the valves and their seats.

The present invention contemplates a self-contained hoist which is built into the machine so that lifting of the valve out of its seat and returning it again is made an easy operation thereby saving both labor and expense and more readily effecting proper working efficiency.

An object, therefore, of the invention is the provision of a self-contained hoist in a valve type vacuum can closing machine wherein the valve or valves may be lifted from their seats for lubricating and cleaning or changing of parts and may be returned again to proper position within their seats without dismantling the machine.

Another object is the provision in such a machine, of electric controls for governing the raising and the lowering of the valves relative to their seats so that in lifting the valves the operation of the hoist ceases when they are clear of their seats or in their desired upper position where they will be easily accessible and also so that upon returning the valves to their seats, the operation of the hoist ceases when the valves are again in their fully seated position.

Still another object is the provision in a machine of this character, of a locking mechanism for locking the valves in a predetermined position in their cycle of rotation or other movement so that movable parts within the valves are properly disposed before the valves are raised, the locking mechanism controlling electric devices which prevent operation of the hoist until

the valves are so positioned and locked and which also prevent operation of the machine while the valves are so locked.

A further object is the provision in such a machine, of elements which prevent operation of the hoist when there is a vacuum in the can closing chamber of the machine and which also prevent operation of the machine while the valves are out of their seats and until they have been replaced and a predetermined vacuum again created in the can closing chamber.

Numerous other objects and advantages of the invention will be apparent as it is better understood from the following description, which, taken in connection with the accompanying drawings, discloses a preferred embodiment thereof.

Referring to the drawings:

Figure 1 is a top plan view of a vacuum can closing machine embodying the instant invention, with parts broken away;

Fig. 2 is a fragmentary front elevation of the upper part of the machine showing the valves in raised position above their seats and showing parts of the hoist for raising and lowering the valves, parts being broken away;

Fig. 3 is a longitudinal section of the upper part of the closing machine, the view being taken substantially along a plane extending through the vertical axes of the valves;

Figs. 4 and 5 are horizontal sectional details taken substantially along the lines 4—4, 5—5 in Fig. 3;

Figs. 6 and 7 are horizontal sections taken substantially along the line 6—6 in Fig. 3, and showing in different positions parts of one of the valves and the mechanism for locking the valve in a predetermined position before raising, parts being broken away;

Fig. 8 is a sectional detail of the valve locking mechanism, the view being taken substantially along the line 8—8 in Fig. 7, with parts broken away;

Figs. 9 and 10 are sectional details showing different positions of parts of the electric control devices associated with the valve locking mechanism, the sections being taken substantially along the line 9—9 in Fig. 3;

Fig. 11 is a horizontal sectional detail taken substantially along the line 11—11 in Fig. 10; and

Fig. 12 is a wiring diagram of the electric circuits utilized in the machine.

As a preferred embodiment of the invention the drawings disclose the principal parts of a vacuum

can closing machine of the character shown in United States Patents 1,969,717, issued August 14, 1934, on "Vacuum machine" and 1,985,883, issued January 1, 1935, on "Can feeding machine". Un-sealed cans with their covers loosely held in place as by clinching or otherwise, are introduced into a vacuum chamber where can and cover are united in a sealing connection as by an inter-folding of their parts or in any other suitable 10 manner.

The cans are introduced into the vacuum chamber and are discharged therefrom by way of rotating entrance and exit valves which are provided with suitable pockets in which the cans are carried. Cam actuated fingers in the pockets of the entrance valve sweep the pocketed cans carried by this valve into the vacuum chamber at the proper time while similar fingers in the pockets of the exit valve sweep the cans carried by it, out 20 onto a table or other suitable place of discharge.

Each of the valves is removably seated in and is partially surrounded by a housing which prevents the entrance of air into the vacuum chamber as the valves rotate. Closely connected with 25 the valves is the hoisting mechanism for lifting the valves from their seats to permit cleaning and lubricating and for returning them again into fully seated position. It is to this feature that the invention is particularly directed.

Only sufficient of the can closing machine is herein illustrated and described to provide a clear understanding of the present invention, the hoisting mechanism being shown in some detail.

Such a disclosure preferably embodies a main 35 supporting frame or housing 11 (Fig. 3) having mounted thereon an auxiliary housing 12. These housings enclose a vacuum chamber (indicated by the numeral 13) into which cans 14, having loosely applied covers 15, are introduced for vacuumizing and closing or sealing.

The chamber 13 is vacuumized in any suitable or usual manner as by means of a suction pump or vacuum tank (not shown) which communicates with a pipe line 17 (Fig. 1) leading from the 45 vacuum chamber. The vacuumized cans are closed or sealed in the usual manner by a suitable seaming head 18 (Fig. 3) which is disposed in the vacuum chamber. The seaming head is preferably mounted in a bearing formed in the housing 12.

The cans 14 are delivered into the vacuum chamber 13 and are discharged therefrom through openings 21 formed in opposite side walls of the frame 11 and by way of rotatable entrance and 55 exit valves 24, 25 disposed adjacent these openings. The valves operate in and are partially surrounded by valve seats 26, 27 formed in housings 28, 29 bolted to the sides of the main frame.

The valves 24, 25 are rotated in their seats 60 26, 27 through tongue and groove driving connections 31 with flanged hubs 32 which in turn are keyed to vertical drive shafts 33. The shafts are journaled in bearings 34 formed in brackets 35 which are secured to the sides of the main frame. 65 These shafts are rotated in unison in any suitable manner.

The valves are provided with a plurality of spaced can carrying pockets 37 into which the cans 14 are deposited in the usual manner. Each 70 pocket is provided with a finger 38 mounted on a vertical pin 39 carried in a bearing 41 of the valve, the pin being periodically rocked by a cam 42 mounted on top of each valve. It is these fingers which sweep the cans from the pockets of 75 the entrance valve into the vacuum chamber as

the valve rotates. Similar fingers in the exit valve sweep the sealed cans out onto a suitable discharge table 43 (Fig. 1).

Lifting of the valves out of their seats for cleaning and lubricating and the returning of the valves again to their seats is effected by a hoist mechanism indicated broadly by the numeral 55 (Figs. 1, 2 and 3). The hoist mechanism includes a pair of elongated elevator screws 56, 57 vertically and centrally disposed over the tops of the 10 valves 24, 25, respectively.

The upper ends of the elevator screws 56, 57 are rotatably carried in bearings 58 formed in the bottom of separate gear cases 61, 62. Gear case 61 is formed integrally with a bracket 63 secured by bolts 64 to the top of the housing 12. Similarly gear case 62 is formed on a bracket 65 secured by bolts 66 to the top of the housing 12. The elevator screws 56, 57 are identically supported and connected with their respective valves, 15 therefore it is thought that a description of one of them will suffice for both.

The elevator screw 56, for example, carries a bevel gear 67 which is disposed in its gear case 61, and this bevel gear is connected to its elevator screw by a feather 68 (Fig. 3).

The lower end of the elevator screw is engaged in a threaded nut 71 which is provided with a pair of oppositely disposed wings 72 projecting from its sides. The wings extend into vertical 30 elongated slots 73 formed in the side wall of a stationary tube 74 which surrounds the elevator screw. The upper end of the tube is keyed against rotation within a collar 75 formed on the bottom 35 of the gear case.

The lower end of the tube 74 extends below the end of the elevator screw and rests on top of a spacer shaft 77. The top of the spacer shaft is provided with a trunnion 78 which is journaled for rotation in a bearing 79 carried in the lower end of the tube. The spacer shaft extends through a central bore 81 formed in the valve and has its lower end supported in a recess 82 formed in the top of the valve drive shaft 33.

The spacer shaft 77 is smaller in diameter than the bore 81 with the result that the valve is free to float and thus fit more snugly within its seat. The shaft is feathered in the valve which permits raising and lowering of the latter without getting out of alignment with the tongued driving connection 31 as will be herein-after more fully explained. It will be evident that the parts just described as being associated with the elevation screw 56 are duplicated in 45 connection with the elevator screw 57.

The valves 24, 25 carry sleeves 85 which surround the spacer shafts 77. The lower end of each sleeve is formed with an out-turned flange 86. In the case of the entrance valve 24 this 60 flange rests on top of the central hub of the valve and is secured in place by long bolts 87 which are held in the bottom of the valve (see Fig. 3). In the exit valve 25 the flange rests on top of the valve and is secured by cap screws 88. 65

The upper ends of the sleeves 85 extend above the elevator screw nuts 71 and are formed with in-turned flanges 89 which surround the elevator screw tubes 74. A pressure distributing collar 92 (Figs. 3 and 4) is disposed inside each 70 sleeve 85 between the flange 89 and the wings 72 of the nut 71 and is adapted to engage against the sleeve flange when the valve is raised.

By means of this construction and by a rotating movement in one direction of the elevator 75

5 screws 56, 57, the nuts 71 are caused to ride up in the slots 73 of the screw tubes 74, the slots of the stationary tubes preventing turning of the nuts. The lifting pressure of the distributing 10 collars 92 first brings the latter into engagement with the flanges 89 of the sleeves 85 and then lifts the sleeves and the attached valves. This 15 carries the valves away from the driving connections 31 while still maintaining alignment with the latter.

10 The elevator screws 56, 57 are rotated in unison so that both valves are raised or lowered at the same time. This is effected by a cross shaft 15 having its ends mounted in bearings 96 formed in the gear cases 61, 62. The cross shaft carries bevel gears 97 which mesh with and rotate the elevator screw gears 67 when the cross shaft turns.

20 The shaft also carries a slip clutch 98 which is disposed in the gear case 61 and which is provided with a worm wheel 99. The worm wheel meshes with a worm 101 secured to a shaft 102 of a reversible electric motor 103 (Fig. 1) mounted on the bracket 63. This motor is the source 25 of power for rotating the cross shaft 95 in either direction.

25 In raising and lowering the valves 24, 25 the finger timing cams 42 are lifted or lowered with the valves. The cams have no rotative movement at any time and are held against rotation in a manner to permit their raising and lowering with the valves. For this purpose the cams are provided with guide blocks 105, 106 (Figs. 2, 3, 6 and 8) which may be bolted to the tops of the cams 30 or otherwise secured in any suitable manner. The guide blocks engage vertically disposed guide rods 107, 108 carried in suitable bearings formed in the gear case brackets 61, 62, and in the main frame brackets 35. The guide rod 107 is stationary but the rod 108 can be oscillated within 35 its bearings. Rod 108 is rocked on its axis by a handle 109.

35 To prevent damages to the valve fingers 38 when the valves are raised out of their seats the valves are brought to rest in a predetermined position in which position all of the fingers are completely within the valve pockets as shown in Fig. 7. The valves are then locked against rotation by direct holding of the exit valve 25. Since 40 both valves are in effect connected together by the mechanism which rotates them, the locking of the exit valve also serves to lock the entrance valve. This locking is effected by a slide 111 (Figs. 2, 7 and 8) which is carried in a slideway 113 45 formed in the top of the guide block 106. A cover plate 114 secured to the block holds the slide in its slideway.

45 At one end the slide 111 is formed with a locking tongue 116 which is engageable into a 50 notch 117 formed in a collar 118 mounted on and secured to the exit valve sleeve 85. Thus the collar rotates with the valve under normal operation of the machine. When the machine is to be stopped, to prevent locking of the valves it is 55 jogged along or moved slowly as by alternate operation of a start and stop switch device, hereinafter referred to, until a notch 117 is in proper position to be engaged by the locking tongue 116. There are a plurality of these notches 117, one 60 for each pocket in the exit valve, and any one of these notches when engaged by the slide tongue 116 locks the exit valve and through it also the entrance valve against rotation.

65 The slide tongue 116 is moved into engagement 70 with a notch 117 by a cam connection with the

guide rod 108. The end of the slide 111 opposite the tongue end is formed with a curved section 121 (Figs. 6 and 8) which partially surrounds the guide rod and is provided with a pair of inner cam edges 122, 123.

75 The cam edge 122 when the guide rod 108 is in unlocked position (Fig. 6) is held against the rod by a tension spring 124 (Fig. 8) disposed in a recess 125 of the guide block 106. One end of the spring is hooked into a screw eye 126 secured to the guide block while its opposite end is hooked into a similar screw eye 127 secured to the slide 111. This latter screw eye extends through a clearance slot 128 formed in the floor of the slideway 113. A short key 131 fixed in 15 the guide rod 108 engages the cam edge 123 at such a time and holds the slide 111 in retracted or unlocked position.

20 When the guide rod 108 is turned, by means of the handle 109, in a counter-clockwise direction, (i. e., from the position shown in Fig. 6 into that shown in Fig. 7) the key 131 is rocked away from the cam edge 123, this action releasing the slide. In this same movement another key 132 much longer than the first key and located in the opposite side of guide rod 108 moves into engagement with the cam edge 122 and then pushes the slide forward against the resistance of the spring 124 thereby moving the tongue 116 into a notch 117 and hence locking the valves against rotation as already described.

25 The key 132 is of sufficient length to hold the slide 111 in locked position irrespective of the vertical position of the valve. A clearance groove 133 cut in the block 106 provides for clearance 30 of the key and allows for this vertical movement of the valve and the block. A second clearance groove 134 cut in the block 106 provides for freedom of vertical movement relative to the key 131 by allowing the block to clear the key when 35 it is lifted with the valve or returned to lowered position.

40 Turning of the guide rod 108 to lock the valves against rotation also prepares for the lifting of the valves as well as rendering the machine inoperative until the valves are again unlocked. This is done electrically by means of a double pole hoist motor switch 135 (Figs. 9, 10 and 12). The electric circuits utilized for this work will be 45 hereinafter explained in connection with the wiring diagram illustrated in Fig. 12.

45 The switch 135 is mounted on the gear case bracket 65 (Figs. 1, 2 and 3) and is formed with a movable element 136 which at times is engaged by the head of a pin 137 carried in a boss 138 50 formed on the bracket. A cam 139 mounted on the guide rod 108 raises the pin and the movable switch element when the guide rod 108 has been turned into its valve locking position (as shown in Figs. 7, 10 and 11).

55 Before the valves can be raised the vacuum in the vacuum chamber 12 must be broken and the chamber brought under atmospheric conditions. This introducing of air into the chamber may be done in any suitable manner either 60 mechanically or manually. To graphically indicate the establishment of such conditions the drawings disclose a two-way valve 143 (Fig. 1) which is located in the vacuum pipe line 11. The position of the valve as shown connects the 65 chamber 13 with the vacuum pipe line. When the handle of the valve is turned counter-clockwise, the pipe line is cut off and the chamber is 70 opened to the atmosphere.

75 The preventing of the valve lifting action when

there is vacuum in the chamber 13 may be accomplished by a vacuum control device (indicated broadly by the numeral 144) which utilizes an electric switch included in the electric circuits used for operation of the lifting motor 103. This will be further mentioned in connection with the description of the wiring diagram (Fig. 12) to follow.

Such a vacuum control device may comprise a sylphon bellows connected with a mercury switch which may be encased in a suitable housing located on the vacuum supply pipe 17 adjacent the closing chamber. A change of degree of vacuum in the pipe and in the closing chamber acts on the bellows to tilt the mercury switch in accordance with the vacuum condition. This is a well-known form of control which is often used in vacuum closing machines. A suitable device of this character is disclosed in United States Patent 1,841,326 issued to Lewis W. Eggleston January 12, 1932, on "Controlling means".

Provision is also made for limiting the amount of travel of the valves 24, 25 either in their upward movement or in their return. This is done 25 electrically and includes stop switches which may be mounted upon the gear casings 61, 62. These switches are actuated by movable parts of the valves.

In the valve raising action the top of the exit 30 valve 25 when brought into its upper position engages against the lower end of a pin 147 (Figs. 1, 2, 3 and 5) and lifts the pin which opens an electric circuit. This pin is vertically disposed in suitable bearings formed in the gear case 62. At its upper end the pin carries an arm 148 having 35 at its free end a stud 149 which is guided in a bore formed in a cover of the gear case 62. The guide stud is located directly under a movable element 151 of a normally closed stop switch 152 mounted on top of the gear case.

When the valves are returned to their seats, the wing 72 of the elevator screw nut 71 associated with the entrance valve 24 engages against the wall of the tube 74 at the lower end of the 45 slots 73, bringing the nut to rest. The rotating elevator screw 56 thereupon moves endwise in its threaded seat within the then stationary nut lifting vertically in its bearing 58 and sliding in the gear 67 at its feather connection 68, as shown in Fig. 3.

The screw 56 then stops turning but stays in its raised position. In this lifting action the upper end of the screw engages against and raises a movable element 155 of a stop switch 156, the element being carried in a bearing 157 formed in the cover of the gear case 61. The stop switch 156 is mounted on top of the gear case.

This lifting of the movable element opens the switch 156 and breaks the hoist motor holding circuit which includes the switch. The open position of the switch therefore constitutes its normal position and the switch stays open or normal during the operation of the machine. The hoist motor holding circuit together with other 65 associated electrical circuits will now be described.

Reference should now be had to the wiring diagram (Fig. 12). The machine motor for operating the main parts of the apparatus is designated in this diagram by the numeral 165 and electric energy for operating this motor is supplied in any suitable manner as by a generator 171 which also supplies current for the hoist motor as well as for the various control circuits. 70 Current passes from the generator by way of a

three wire system comprising service wires 172, 173, 174 and through a main service switch 175 and a solenoid-operated switch 176 when the latter is closed. In order to close this switch, control circuits comprising a machine pre-starting 5 and a machine starting circuit are used.

When the valves are being lifted by rotation of the screws 56, 57 current for operating the hoist motor 103 is taken from the service wires 172, 173, 174 and is transmitted to that motor by 10 way of service wires 177, 178, 179 and thence through one or the other of motor reversing solenoid-operated switches 181, 182 one of which is closed at the time. The selective closing of switch 181 or switch 182 is effected by the use of 15 control circuits comprising a valve elevating starting circuit or a valve lowering starting circuit which will be fully set forth as the description proceeds.

The control circuits are of the two wire system 20 type and receive electric energy from the generator by way of a step-down transformer 185. The primary side of this transformer is connected to the service wires 177, 178 by wires 186, 187.

The machine pre-starting circuit is only 25 closed when the valves 24, 25 are in proper seated and operating position and unlocked and only when there is a predetermined degree of vacuum within the chamber 13. When in such condition the movable element 136 of the switch 135 is in the position shown in dotted lines, engaging with lower switch contacts 188, 189. Furthermore, when the valve and the vacuum in chamber 13 are in the condition above described a 30 mercury switch 190 of the vacuum control device 144 is in the tilted position indicated in dotted lines, this closing the gap between switch contacts 191, 192.

Electric energy activating the machine pre- 40 starting circuit passes from the secondary side of the transformer 185 through a wire 195, movable element 136 of switch 135, a wire 196, mercury switch 190 at contacts 191, 192, a wire 197, a solenoid 198 and back to the transformer by 45 way of a wire 199. This flow of current energizes the solenoid 198 and thus closes a normally open relay 201.

Relay 201 is included in the machine starting circuit together with machine start and stop 50 switches 202, 203 which control the normal starting and stopping of the machine motor 165. To set the machine in operation the machine starting circuit is closed by momentarily closing the starting switch 202. Electric energy 55 from the generator 171 then passes from service wire 174 through a wire 205, starting switch 202, a wire 206, stop switch 203, a wire 207, closed relay 201, a wire 208, a solenoid 209, a wire 211, back into service wire 172. This flow of current 60 from the transformer energizes the solenoid 209 which in turn closes the machine motor switch 176 thereby transmitting energy from the generator 171 directly to the machine motor 165.

Closing of the machine motor switch 176 automatically 65 establishes a machine holding circuit which maintains continued operation of the motor 165 after release of the starting switch 202. The holding circuit is established by the closing of a single contact 212 which is formed as a part 70 of the motor switch 176 and which closes when the switch is closed. This holding circuit cuts out the starting switch 202. Energy then passes from service wire 174 through contact 212, a wire 213, thence through the stop switch 203, closed relay 75

201, and solenoid 209 returning by way of service wire 172 to maintain the solenoid energized and the motor switch 176 closed.

Provision is made for stopping operation of the machine in case the vacuum condition in the closing chamber 13 should fall below a predetermined degree. For this purpose the machine holding circuit, keeping the machine motor 165 in operation, is maintained under the control 10 of the machine pre-starting circuit. Thus a falling off of the vacuum, as detected by the vacuum control devices 144, immediately tilts the mercury switch 190 in the opposite position (shown in full lines, Fig. 12) so that the gap between the contacts 191, 192 is opened. This breaks the machine pre-starting circuit with the result that the solenoids 198, 209 are de-energized and the machine holding circuit is thus broken causing the machine motor switch 176 to open. This 20 stops the operation of the motor 165 and hence stops operation of the machine. The machine motor cannot then be started again until the degree of vacuum in the closing chamber is high enough to again tilt the mercury switch 190 to 25 close the gap between its contacts 191, 192.

Normal stopping of the machine is effected by opening the machine stop switch 203. This will deenergize the solenoid 209 and open the machine motor switch 176 even if sufficient vacuum is 30 maintained in the closing chamber.

The valve elevating starting circuit and the valve lowering starting circuit which are associated with the operation of the hoist motor 103 for rotating the elevator screws 56, 57 in raising 35 and lowering the valves 24, 25 also include the hoist motor switch 135 and the mercury switch 190, these switches being closed in such a manner as to entirely cut out the circuits associated with the machine motor 165. It will be remembered 40 that before raising the valves the vacuum in the can closing chamber 13 must be dissipated, the machine stopped, and the valves locked in a predetermined position as hereinbefore explained.

Locking of the valves disengages the movable 45 element 136 of the switch 135 from the contacts 188, 189 and brings it into engagement with a pair of new contacts 214, 215 shown in full lines in Fig. 12. This breaks the machine motor circuit and prevents operation of the machine motor 165 until the valves are again unlocked which 50 ordinarily does not take place until after the valves have been raised out of their seats and again returned.

Dissipation of the vacuum in the can closing 55 chamber 13 rocks the mercury switch 190 to a position where the contacts 191, 192 are opened as has already been described. The switch 190 also has a pair of contacts 216, 217 which are closed when contacts 191, 192 are opened and are 60 opened when contacts 191, 192 are closed. It is the closing of contacts 216, 217 which permits use of the valve elevating circuit and the holding circuit associated therewith. This will now be explained.

65 To raise the valves 24, 25 out of their seats, the valve elevating starting circuit is completed by pressing a starting switch 218 to bring it into its starting position, indicated by dotted lines in Fig. 12. Electric energy from the secondary side of the transformer 185 then passes along wire 195, a wire 219, switch 135, a wire 220, an emergency switch 221, a wire 222, contacts 216, 217 of switch 190, a wire 223, stop switch 152, a wire 224, a valve lowering start switch 225, a wire 226, 70 closed starting switch 218, a wire 227, a solenoid 75

228, wires 229, 231, 199 back to the transformer.

Electric energy passing through this circuit energizes the solenoid 228 which closes the hoist motor switch 181. Closing of this switch permits electric energy from the generator 171 to 5 pass from the service wires 177, 178, 179 through the switch 181, wires 236, 237, 238 and thence into the motor 103 causing it to turn the elevator screws 56, 57 in the proper direction for raising the valves 24, 25 out of their seats as hereinbefore explained.

Since closing of the starting switch 218 is only a momentary action, a valve elevating holding circuit is established simultaneously with the closing of the motor switch 181 and this keeps 15 the motor 103 in continuous operation until the elevating of the valves is completed, this being when the valves are clear of their seats.

The valve elevating holding circuit is established by closing of a single contact 242 formed 20 as a part of switch 181 and which automatically closes with the switch. Thus when the starting switch 218 resumes its normal open position as shown in full lines in Fig. 12, energy from the transformer passes from the wire 226 along a 25 wire 243, through contact 242, a wire 244, wire 227, solenoid 228, and wires 229, 231, 199 back to the transformer. This circuit maintains the solenoid 228 energized while the starting switch is open and thus keeps the motor switch 181 30 closed.

When the valves 24, 25 reach the top of their desired travel they open the stop switch 152 as hereinbefore explained. This breaks the valve elevating holding circuit just described. The 35 solenoid 228 is thus deenergized and the switch 181 is opened in the usual way. This stops the motor 103 and further rotation of the elevator screws 56, 57 which thus stops further raising of the valves. 40

Lowering of the valves 24, 25 again to position within their seats is effected by similar circuits which are established to cause motor 103 to rotate the elevator screws 56, 57 in a reverse direction. A valve lowering starting circuit is established 45 by pressing the starting switch 225 and moving it into the position shown in dotted lines in Fig. 12. Electric energy from the transformer 185 is then transmitted by way of wires 195, 219, switch 135, wire 220, emergency switch 221, wire 50 222, a connecting wire 246, closed stop switch 156 (dotted position), a wire 247, starting switch 218, a wire 248, closed starting switch 225, wires 249, 251, a solenoid 252, wires 253, 231, 199 back to the transformer. 55

Energy passing along this valve lowering starting circuit energizes the solenoid 252 which closes the hoist motor switch 182. Closing of this switch permits energy to pass from the service wires 177, 178, 179, through the switch 182, and wires 256, 60 257, 258, into the hoist motor 103. This flow of current through the motor being in the opposite direction to that described for the valve elevating action causes the motor and the screws 56, 57, to rotate in reverse and hence to lower the valves 65 into their seats.

A valve lowering holding circuit is established to maintain continued operation of the hoist motor after the starting switch 225 is released and returned to its normally open position. This 70 holding circuit is established by a single contact 261 which is associated with the main switch 182 and which closes when the main switch closes. Electric energy then passes from the wire 248, along a wire 262, contact 261, wires 263, 251, 75

solenoid 252, wires 253, 231, 199 back to the transformer. This keeps the solenoid 252 energized and hence maintains the main switch 182 in closed position during lowering of the valves.

- 5 When the valves 24, 25 are again returned within their seats, the closed stop switch 156 is again opened to its normal position as hereinbefore explained to break the valve lowering holding circuit. The solenoid 252 becoming de-energized, 10 causes the main switch 182 to open and to stop the hoist motor 103. The valves 24, 25 may now be unlocked after which if the machine is to be operated the foregoing steps will be carried out.

A brief recapitulation of the operation of the 15 elevator screws 56, 57 through one complete cycle including raising and lowering of the valves 24, 25, will now be given. Before actually beginning the cycle and as a preliminary step, the machine motor 165 must necessarily be stopped. Then the 20 exit valve 25 is manually locked by movement of the locking handle 109 and this also locks valve 24. The movable element 136 of the switch 135 is thereby brought into engagement with the upper contacts 214, 215 which are thus included as a 25 part of a circuit which connects with the hoist motor 103. Electric switch 152 at this time is closed and switch 156 is open.

The starting switch 218 is pressed in and the 30 cycle begins as current established by the switch energizes the hoisting motor 103 and the elevator screws 56, 57 start rotation. There is a slight time lag before the entrance valve 24 is lifted as its turning screw 56 moves down within the nut 71 permitting the descending screw head to release the movable element 155 of switch 156 which action closes the switch. Both valves 24, 25 move out of their seats and travel up along the lengths of their rotating screws 56, 57.

When the raised valves reach their upper limit 35 of travel the exit valve 25 opens switch 152 by engagement with the movable switch element 151. This breaks the current and stops the motor 103 and the screws 56, 57 cease rotation.

To return the valves to their seats starting 40 switch 225 is pressed in and the motor 103 thereupon operates in a reverse direction. It should be recalled that switch 156 is now closed and switch 152 is open. The motor rotating the screws 56, 57 in a reverse direction lowers the 45 valves into their seats. The movable element 151 upon being disengaged closes the switch 152.

The effect of the final phase of rotation of the elevator screw 56 after the entrance valve 24 is fully seated is to slightly elevate or back up the 50 screw and to lift its head against and to raise the movable element 155 of the switch 156 thereby opening the switch. This breaks the hoist motor reverse circuit and the motor 103 stops, the screws 56, 57 cease turning. The cycle is completed.

The valves thus fully reseated may then be unlocked or freed for rotation and for normal machine operation by manipulation of the locking handle 109.

65 It will be recalled that an emergency switch 221, has been included in the valve elevating and valve lowering, starting and holding circuits. This is used to manually terminate the action of any of these circuits at any time before completion of their respective cycles. It is therefore a safety feature and by manually opening a circuit at this switch the valves can be brought to rest in any desired position whether they are being raised or lowered.

70 75 It is thought that the invention and many of

its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a vacuum machine for cans, the combination of a housing enclosing a vacuum chamber and having openings for the passage of cans therethrough, valve seats connected with said housing adjacent said openings, valves floatingly disposed in and upwardly from said seats for normally conveying cans into and out of said vacuum chamber, rotatable elevator screws anchored in said housing as a permanent part thereof and rotatably connected with said valves for moving the latter vertically relative to their seats for lubrication and cleaning, and driving elements for rotating said elevator screws in one direction to lift said valves out of their seats and in the opposite direction to return them again to fully seated position. 25

2. In a vacuum machine for cans, the combination of a housing enclosing a vacuum chamber and having openings for the passage of cans therethrough, valve seats secured to said housing adjacent said openings, rotatable valves disposed in and upwardly movable from said seats for conveying cans to and from said vacuum chamber, rotatable elevator screws anchored in said housing as a permanent part thereof and rotatable in two directions having connection with said valves for moving the latter vertically to clear their seats or to reseat the valves after clearance, a driving element connecting with said elevator screws for rotating them in unison, and a reversible electric motor for rotating said driving element in either direction to raise and lower said valves in unison. 30

3. In a vacuum machine for cans, the combination of a housing enclosing a vacuum chamber and having openings for the passage of cans therethrough, valve seats in said housing adjacent said openings, rotatable valves disposed and upwardly movable in said seats for conveying cans to and from said vacuum chamber, means for rotating said valves, means self-contained in said housing and including an electric motor for lifting the valves from their seats, and electric devices operable by engagement with one of said valves while being lifted by said lifting means for stopping operation of said electric motor when said valves are in a predetermined lifted position. 45

4. In a vacuum machine for cans, the combination of a housing enclosing a vacuum chamber and having openings for the passage of cans therethrough, valve seats connected with said housing adjacent said openings, valves disposed and upwardly movable in said seats for conveying cans into and out of said chamber, means located in said housing and including an electric motor for removing the valves from their seats or for again returning them to fully seated position, means for starting said motor to remove said valves from or to return them to their seats, and electric devices for terminating operation of said electric motor and hence stopping further seat movement of said valves when the latter are returned to fully seated position. 60

5. In a vacuum machine for cans, the combination of a housing enclosing a vacuum chamber

- and having openings for the passage of cans therethrough, valve seats connected with said housing adjacent said openings, valves disposed and upwardly movable in said seats for conveying cans into and out of said chamber, fingers in said valves for ejecting cans therefrom, cams adjacent said valves for actuating said fingers, means self-contained in said housing for removing the valves from their seats or for again rendering them to fully seated position and for moving the cans with the valves, and devices engaging said cams for maintaining said fingers in predetermined relation with said valves while the latter are moved relative to their seats.
- 5 6. In a vacuum can closing machine, the combination of a housing enclosing a vacuum chamber and having openings for the passage of cans therethrough, can closing mechanism located in said vacuum chamber for closing said cans in vacuum, valve seats in said housing adjacent said openings, rotatable valves disposed and upwardly movable in said seats for conveying cans to and from said closing mechanism, a device for dissipating the vacuum in said closing chamber, instrumentalities for locking said valves against rotation and in a predetermined position of their cycle, means self-contained in said housing for removing the valves from their seats or for again returning them to fully seated position while so locked and while said vacuum is dissipated from said chamber, and electric devices operable by said locking instrumentalities for rendering the said can closing mechanism inoperable while the valves are locked.
- 10 7. In a vacuum machine for cans, the combination of a housing having a valve seat, a valve rotatably disposed in said seat and adapted to confine a vacuum chamber, said valve presenting cans for vacuumization in said chamber, and self-contained means within said housing and axially disposed relative to said valve for lifting the latter to a position clear of its seat.
- 15 8. In a vacuum machine for cans, the combination of a housing having a valve surrounding seat, a valve disposed for vertical movement within and relative to said seat and adapted to confine a vacuum chamber, said valve being adapted to introduce cans into said chamber for vacuumizing therein, and means located in said housing and operatively connected to said valve for moving the valve vertically relative to its seat to permit lubricating and cleaning.
- 20 9. In a vacuum machine for cans, the combination of a housing enclosing a vacuum chamber and having an opening for the passage of cans therethrough, a valve surrounding seat connected with said housing adjacent said opening, a valve movably disposed within said seat for moving cans relative to said housing and said vacuum chamber, and means located in said housing and operatively connected to said valve for elevating the valve from its seat and for thereafter lowering it into fully seated position.
- 25 10. In a vacuum machine for cans, the combination of a housing having a valve seat, a valve rotatably disposed and upwardly movable in said seat and adapted to confine a vacuum chamber, said valve presenting cans for vacuumization in said chamber, means self-contained in said housing and including a rotatable elevator screw mounted on the vertical axis of said valve and anchored in said housing as a permanent part thereof and rotatably loosely connected with the valve for lifting it to a position clear of its seat, and means for rotating said elevator screw when said vacuum chamber is not under vacuum.
- 30 11. In a vacuum machine for cans, the combination of a housing enclosing a vacuum chamber and having openings for the passage of cans therethrough, valve seats connected with said housing adjacent said openings, valves disposed and upwardly movable in said seats for conveying cans to and from said closing chamber, a device for dissipating the vacuum in said closing chamber, means self-contained in the said housing for removing the valves from their seats or for again returning them to fully seated position while the vacuum of said chamber is dissipated, means for actuating said valve removing or said valve returning means, and manually operated electric devices for stopping said actuating means to arrest movement of said valves at any desired position in their path of travel during their removal from or return to their seats.
- 35 12. In a vacuum machine for cans, the combination of a housing enclosing a vacuum chamber and having openings for the passage of cans therethrough, valve seats secured to said housing adjacent said openings, rotatable valves disposed in and upwardly movable from said seats for conveying cans to and from said vacuum chamber, means for dissipating the vacuum in said chamber, means self-contained in said housing and including an electric motor for removing the valves from their seats, and means operable only after said vacuum has been dissipated from said chamber for effecting said valve removing operation.
- 40 13. In a vacuum machine for cans, the combination of a housing enclosing a vacuum chamber and having openings for the passage of cans therethrough, valve seats connected with said housing adjacent said openings, rotatable valves disposed in and vertically movable relative to said seats for conveying cans into and out of said chamber, instrumentalities for locking said valves against rotation and in a predetermined position of their cycle, and means self-contained in said housing for moving the valves vertically from their seats or for again returning them to fully seated position while so locked.
- 45 14. In a vacuum machine for cans, the combination of a housing enclosing a vacuum chamber and having openings for the passage of cans therethrough, valve seats connected with said housing adjacent said openings, rotatable valves disposed in and vertically movable relative to said seats for conveying cans into and out of said chamber, instrumentalities for locking said valves against rotation and in a predetermined position of their cycle, and means self-contained in said housing for moving the valves vertically from their seats or for again returning them to fully seated position while so locked.
